US0D1038998S

(12) **United States Design Patent** (10) **Patent No.:** **US D1,038,998 S**
(45) **Date of Patent:** **** Aug. 13, 2024**

(54) **PORTABLE PUMP**

(71) Applicant: **Shenzhen shenguanghuan Technology Co., Ltd.**, Guangdong (CN)

(72) Inventor: **Xuanqiong Peng**, Hubei (CN)

(73) Assignee: **Shenzhen shenguanghuan Technology Co., Ltd.**, Guangdong (CN)

(**) Term: **15 Years**

(21) Appl. No.: **29/922,183**

(22) Filed: **Dec. 21, 2023**

(51) LOC (14) Cl. **15-02**

(52) U.S. Cl.

USPC **D15/7**

(58) **Field of Classification Search**

(57) **CLAIM**

The ornamental design for a portable pump, as shown and described.

DESCRIPTION

FIG. 1 is a front, right and top perspective view of a portable pump, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 2.

The broken lines depict portions of the portable pump that form no part of the claimed design.

The dot-dash broken lines in FIGS. 2 and 9 depict the boundaries of the enlargements that form no part of the claimed design.

1 Claim, 9 Drawing Sheets
